EMIL DEISTER, OF FORT WAYNE, INDIANA, ASSIGNOR TO THE DEISTER CONCENTRATOR COMPANY, OF FORT WAYNE, INDIANA, A CORPORATION OF INDIANA.

DRIVING MECHANISM FOR ORE-CONCENTRATORS.

1,101,486.

Specification of Letters Patent. Patented June 23, 1914.

Application filed August 1, 1907. Serial No. 386,502.

To all whom it may concern:

Be it known that I, EMIL DEISTER, a citizen of the United States of America, and resident of Fort Wayne, in the county of Allen and State of Indiana, have invented certain new and useful Improvements in Driving Mechanism for Ore-Concentrators, of which the following is a specification.

10 This invention relates to improvements in driving mechanism for ore concentrators, and the object thereof is to provide means for effecting differential reciprocating motion of the desired sharpness and character, 15 without serious wearing of the frictional surfaces of the various parts. The class of ore concentrators with which this invention is intended for use, particularly, is that in which is employed a table having a concentrating surface across which pulp flows by the attraction of gravitation, and which has applied to it a concentrating motion to drive out of the path of the gravitational flow of the pulp the mineral particles that come 20 into contact with the concentrating surface, and thus separating the mineral from the gangue. The term "concentrating motion" used herein, is intended as meaning only such movement as will, when applied to the 25 table, drive the heavier constituents of the pulp upon the surface of the table out from the path of its gravitational flow thereover, so that it thereby becomes separated from the lighter constituents thereof. This object is 30 accomplished by the construction illustrated in the accompanying drawings, in which:

Figure 1 is a side elevation of the machine, shown partly in section; Fig. 2 is a side elevation of the opposite side from 40 Fig. 1; Fig. 3 is an end view; Fig. 4 is a detail in perspective showing an adjustable sleeve bearing.

Similar numerals of reference indicate corresponding parts throughout the several 45 views and referring now to the same:

1 is a frame-casting mounted upon a base 2 and having opposite bearings 3 and 3' respectively. In the bearing 3' is adjustably secured a sleeve 4 which has an eccentric cylindrical extension 5. The sleeve 4 has a central bore 6 which extends through the

extension 5 eccentric of the latter, and a rotatable shaft 7 extends through the bore 6 and rests with one end in the main bearing 3. Upon the shaft 7, between the bearings 3 and 3', is fixed an eccentric 8 which has thereon a loose roller 9.

Upon the eccentric 5 are two loose pulleys, 10 and 11 respectively, and upon the extending end of the shaft 7, adjacent the outer end of the extension 5, is fixed a box-crank 12. A pin 13 projects from the side of the pulley 10 and has loosely mounted thereon a block 14 which slides within the box-crank as the pulley 10 rotates. The pulley 11 runs idle and carries the driving belt when the latter is shifted from the driving pulley 10.

A pair of brackets 15 depend from the frame 1 and support a shaft 16 at their lower ends, and upon said shaft, between the brackets, is mounted a lever 17 which is angular in form, and has at one end an upright slotted head 18, and at the other end a concave bearing face 19 which bears 75 against the roller 9. A vertically adjustable block 20 is mounted in the slotted head 18 and supports a horizontal shaft 21, and a yoke 22 is arranged astride the head 18 with its arms connected with the shaft 21. The yoke is connected with a reciprocating table 23 by means of a connecting rod 24, and the table is held in forward position by means of a spring 25. The tendency of the table is to move forward, due to the action of the 80 spring, and this has the effect of holding the lever constantly in contact with the roller 9.

In the operation of this invention, the drive-wheel 10 is revolved uniformly, in the direction indicated by the arrow, by belt 90 or otherwise, and the shaft 7 will be rotated differentially because of its connection with the driving wheel 10 and its eccentric relation therewith. It will appear that the shaft in rotating through a portion of its 95 cycle moves with greater velocity than through the remaining portion, and the eccentric 8 is therefore actuated likewise. During the rotation of the eccentric 8, the roller 9 moves upon the concave face of 100 the lever 17, rolling to and fro, and said lever thereby is oscillated upon the shaft

16 with a differential movement which is due; first, to the throw of the eccentric 8 and travel of the roller upon the curved face 19 of the lever; and second, to the 5 initial differential rotation of the shaft 7. By adjusting the eccentric 5 so that the accelerated portion of the cycle of the shaft 7 occurs simultaneously with that imparted by the roller to the lever 17, the resultant 10 differential action becomes magnified, and it will therefore appear that the differential motion, inherent in the roller and lever, is accelerated during the quickened portion of its cycle by the similar quickened movement 15 of the shaft 7, and the consequent movement imparted to the table is quicker and sharper at the forward end of the stroke and slower and more gentle at the other, than is obtainable by a single differential 20 mechanism. The two differential mechanisms are used jointly, but are essentially of different character: The roller and lever mechanism that connects the table and shaft generates and imparts to the table a 25 concentrating movement; and the box-crank mechanism that connects the drive-wheel and shaft, generates and imparts to the shaft a differential rotary movement. The resultant movement imparted to the table is 30 therefore the concentrating movement generated by the one mechanism accentuated by the differential action of the other mechanism. Thus is effected an accentuated concentrating movement.

35 Having described my invention what I claim as new and desire to secure by Letters Patent is:—

1. In an apparatus for the production of differential reciprocating movements a 40 shaft; a differential motion generating mechanism in connection with the shaft to rotate the same differentially; an actuating lever having engagement with the shaft to be driven thereby; and means to adjustably 45 vary the position of the former mechanism relative to the shaft to shift the period of maximum differential movement in the cycle of the shaft.

2. In an apparatus for the production of 50 differential reciprocating movements a shaft journaled therein; a fixed eccentric on the shaft; a roller loosely mounted on the eccentric; a pivoted lever having a curved bearing face, the said roller having rolling 55 contact on said face and being adapted to actuate the lever; a drive pulley mounted eccentrically of the shaft and having a drive pin; a box crank rigidly fixed on the shaft and having a sliding block therein which has 60 connection with said pin.

3. In an apparatus for the production of differential reciprocity, a frame, an eccentric shaft journaled in the frame, a roller

loosely mounted on the shaft, a pivoted lever having a curved face adapted to make 65 contact with the roller, a driving pulley eccentrically mounted relatively to the axis of the eccentric shaft and having a laterally projecting pin, a crank secured to the shaft, and a sliding block in the crank engaging 70 the pin.

4. In an apparatus for the production of differential oscillations a differentially rotated shaft, a roller carried by the shaft eccentric thereto; a pivoted lever engaging 75 said roller; means to hold the pivoted lever in contact with the roller, a frame casting for the shaft; a sleeve adjustably secured in the frame casting and having an eccentric cylindrical extension, said sleeve affording a 80 bearing for the shaft, a drive wheel loosely mounted on the extension and means connecting the drive wheel and shaft adapted to rotate the latter differentially.

5. In an apparatus for the production of 85 differential reciprocations a frame casting, a sleeve adjustably mounted in the frame casting and having a cylindrical eccentric extension, a shaft mounted centrally in the sleeve and extending through said extension, 90 a drive wheel loosely mounted on said extension, means connecting the drive wheel and shaft to rotate the latter differentially.

6. In an apparatus for the production of differential reciprocating movements a 95 frame, a sleeve adjustably secured in the frame and having an eccentric extension, a shaft extending concentrically through the sleeve, a drive wheel mounted upon the extension and adapted to rotate thereon, a 100 differential motion generating mechanism in connection with the shaft, and a rotary differential mechanism in connection with the drive wheel and shaft adapted to actuate the shaft and accentuate the 105 differentiation of the reciprocating motion generated by the former mechanism.

7. In an apparatus for the generation of reciprocating movements, a frame; a sleeve adjustably secured in the frame and having 110 an eccentric extension, a shaft extending concentrically through the sleeve, a drive wheel mounted on the extension of the sleeve and adapted to rotate thereon, a differential mechanism in connection with the shaft, an 115 actuating lever adapted to be operated by the mechanism, and a differential mechanism in connection with the drive wheel and shaft adapted to actuate the latter.

8. In apparatus for the production of 120 differential reciprocity, a frame, a shaft suitably journaled in the frame, a bearing through which the shaft extends eccentrically adjustably secured to the frame, a drive wheel mounted upon the bearing and adapted to rotate thereon, an oscillating lever, a

mechanism in connection with the shaft adapted to actuate the lever and a differential mechanism in connection with the drive wheel and shaft adapted to actuate the latter said bearing being adapted to be shifted to adjustably vary the period of maximum differential action of the shaft.

In testimony whereof I affix my signature, in presence of two witnesses.
